TIME SWITCH

Robert Hermann, Swampscott, Mass., assignor to
 General Electric Company, a corporation of
 New York

Application January 21, 1941, Serial No. 375,152

6 Claims. (Cl. 200—39)

My invention relates to time switches and in particular to time switches of the type including a clock dial where the levers for setting the time or times of operation of the switch mechanism are adjustable about such dial. The principal object of my invention is the elimination of gearing or its equivalent between the setting levers and the time actuated switch operating mechanism in time switches of the type above mentioned to the end that the mechanism may be simplified and made less costly in construction without sacrificing reliability and accuracy.

The features of my invention which are believed to be novel and patentable will be pointed out in the claims appended hereto. For a better understanding of my invention, reference is made in the following description to the accompanying drawing in which Fig. 1 represents a perspective front view of a time switch embodying my invention. Fig. 2 represents a horizontal cross-section view taken through the center of the device of Fig. 1 and Fig. 3 is an exploded view of the switch setting levers and the time actuated switch operating mechanism with which the levers cooperate.

The invention will be described as applied to a non-repeat form of time switch often employed for turning on an electric range at a predetermined adjustable time and off at a later predetermined adjustable time and thereafter to remain idle insofar as its switching operations are concerned until reset or cocked, although the clock thereof may continue to run and indicate time. The external appearance may be as represented in Fig. 1 where 10 represents a suitable casing, 11 a twelve hour clock dial on which hour and minute hands 12 and 13 indicate the time of day and about which "on" and "off" switch setting levers 14 and 15 may be adjusted. For reasons which will appear later, the central portions 16 and 17 of the dial rotate as a unit and the hour hand 12 may be painted thereon. Part 16 may be omitted, but its presence improves the appearance and increases the visibility of the clock hands. The "on" and "off" levers extend through a circular opening 18 between the central rotary part of the dial and the outer stationary part 11 of the dial. 19 represents a lever extending through a slot 20 in a wall of the casing, which lever serves both for manually cocking the switch and as an indicator of the condition of the switch. In the illustration, Fig. 1, the switch is cocked or "set" as indicated by the position of lever 19, to go "on" at 12:35 as indicated by the position of lever 14, and to go "off" at 5:30 as indicated by the position of lever 15. When the switch goes on, lever 19 will move to the center of slot 20 opposite the indication "on" and when the switch goes off, lever 19 will move further to the rear of slot 20 opposite the indi-

cation "off" where it will remain until it is manually moved to the "set" position.

A preferred form of mechanism embodying the invention is illustrated in Figs. 2 and 3. In Fig. 5 2, 21 represents any suitable form of clock motor which is connected to drive the minute hand 13 and its shaft 22 through gears 23 and 24 and a slip friction clutch indicated as a spring washer 25 inserted between gear 24 and a gear 26, the latter being fast on shaft 22. Gear 24 is not secured directly to shaft 22 but may rotate thereon to permit manual setting of the clock hands by reason of slipping of the clutch. Under normal operating conditions the clutch does not slip and hence the minute hand is rotated in a clockwise direction once per hour. The hour hand disk comprising the parts 16 and 17 with the hour hand 12 are secured to hollow shaft 27 and this shaft is driven clockwise one revolution in 10 twelve hours through a gear 28 secured to hollow shaft 27, back gears 29 and 30 and gear 26 on minute hand shaft 22. The clock shaft assembly has bearings in clock plates 31 and 32 and the central portion 17 of the rotary hour dial has a 15 rearward extension 33 which rides lightly on a collar 34 fastened to and comprising a part of the "off" switch setting lever 15. Collar 34 also has a rearward extension fitting inside of a collar 35 fastened to and comprising a part of the 20 "on" lever 14. Collar 35 has a bearing fit within an opening in a clock plate 36 and is secured from axial displacement in such opening by its T-shaped cross-section and a spring washer 37 compressed between plate 36 and the annular 25 part of lever 14 which embraces and is secured to collar 35. The collars 34 and 35 are concentric to and may be rotated about the axis of the clock shafts by lever projections 14 and 15 and they have sufficient friction against such movement to stay in any rotary position to which 30 adjusted. The friction of collar 34 against rotary movement is preferably increased by a thin annular collar 38 fastened to lever 15 and inserted between the forward face of clock plate 36 and spring washer 37. These switch time setting collars are thus normally stationary and provide a bearing surface on which part 33 of the hour dial 17 rides and by means of which the collar 34 is held from forward axial movement. 35 The inner peripheries of collars 34 and 35 are concentric with the clock shafts but spaced therefrom and have radial slots 39 and 40 cut therein of such dimensions as to permit a resilient catch member 41 to pass therethrough when the catch member is rotated into alignment with such openings. 40 The catch member part 41 is secured to a sleeve 42 slidably mounted on hollow shaft 27 but forced to rotate with the shaft by reason of the fact that 45 a portion of the catch member 41 engages in a 50 55 60

longitudinal key way or slot 43 in shaft 27, forming a splined connection between the sleeve 42 and shaft 27. The parts 41 and 42 therefore rotate with the hour shaft 27 at one revolution in twelve hours. The sleeve 42 comprises a switch operating member and is preferably provided with a disk 44 of insulating material for making contact with movable switch contact members which may be arranged about the periphery of the disk and one of which is shown at 45.

The switch operating member is shown in the cocked or set position. In such position a spring 46 is compressed between the rear of the sleeve 42 and the clock plate 32. This spring urges the switch operating member towards the front of the clock but such movement is normally prevented by reason of the fact that the forward turned-in end of resilient catch 41 abuts against the collar 35. The parts 41 and 35 thus comprise a catch stop. When, however, catch 41 rotating with shaft 27 rotates into alignment with the slot 39 in collar 35 the switch operating member 42-44 moves forward sliding on shaft 27 until the forward end of catch 41 strikes against collar 34 comprising another stop plate. In this intermediate position of the switch operating member, the contact member such as 45, due to its bent shape is forced outward to make contact with a stationary contact member such as shown at 47, thereby closing the switch represented. This is the "on" position of the switch.

When the catch 41 now rotates into alignment with the slot 40 in stop plate collar 34, the switch operating member 42 again moves forward until stopped by its enlarged hub part striking against collar 35 or otherwise. This allows the disk 44 to move from beneath the forward sloped end of switch member 45 and allows the switch to open. This is the "off" position of the mechanism. In this condition the spring 46 is preferably under little or no tension so that no material friction is encountered by reason of parts 42 and 35 rubbing together as part 42 continues to rotate.

The cocking lever 19 is pivoted at 48 and its inner end is forked and is provided with trunnion pins, one of which is indicated at 49, which pins extend inward and ride in a groove 50 in the rear end of sleeve 42. The lever thus moves with the sliding movement of the sleeve 42 and produces the indications "set," "on" and "off" as explained in connection with Fig. 1 for the corresponding positions of the switch operating mechanism.

It will be noted that the shape of resilient catch 41 is such that if the sleeve 42 be forced to the rear to compress the spring 46, the catch may spring radially inward and pass beneath the inner peripheries of collars 34 and 35 without being rotated into alignment with the slots 39 and 40. The recess 43 in hollow shaft 42 is of sufficient depth to permit the forward end of spring catch 41 to be sprung towards the shaft and pass beneath the collars in any relatively rotary position of these parts. Hence the handle 19 may be pulled forward manually from the "off" to the "set" position, or from the "off" to the "on" position, or from the "on" to the "set" position at any time to position the switch operating parts accordingly. If the mechanism be in the "set" or the "on" position and it is desired to move it to the "on" or to the "off" position without waiting for the catch 41 to be rotated into alignment with the slots 39 or 40 in collars 35 and 34 by the clock, then the lever 14 or 15 or

both may be turned to rotate the slots 39 or 40 or both into alignment with catch 41. For example, in Fig. 1 if the lever 14 be rotated into alignment with the hour hand 12, the lever 19 will move to the "on" position and the switch will then be closed. The switch may thus be manually operated in either direction any desired amount at any time.

In Fig. 1 it will be noted that the switch has been cocked or set subsequent to the time setting of the "on" lever 14. This setting of the device means that the switch will not be automatically operated until the hour hand next passes the "on" lever. For example, let it be assumed that the clock time indicated is 1:20 P. M. No automatic switch operation will occur until the next 15 12:35 A. M. when the switch will be turned on and it will then be turned off at 5:30 A. M. If, however, the "on" lever 14 is positioned ahead 20 of the hour hand, say at 2:00 P. M. with the other conditions remaining unchanged, the switch will then go on at 2:00 P. M. and off at 5:30 P. M. The use of the principles involved in this switch is not confined to the particular 25 switching arrangement shown and described. Several switches can be operated by the same mechanism and some may be turned on when others are turned off. A twenty-four hour time dial and timing arrangement may be used and the number of automatic operations that may be performed by the progressive step-by-step forward movement of sleeve 42 may be increased by adding more slotted collars such as 34 and 35 and correspondingly extending the axial movement range of the sleeve 42.

It will be noted that the use of a rotary inner dial with the hour hand painted thereon allows such dial to be supported on the hour hand shaft with the levers 14 and 15 freely accessible for 30 manual adjustment concentric with the clock dial. No gearing or its equivalent is required to be operated through the levers 14 and 15 and a single dial is used for telling time and for setting of the switch.

45 In accordance with the provisions of the patent statutes, I have described the principle of operation of my invention together with the apparatus which I now consider to represent the best embodiment thereof, but I desire to have it understood that the apparatus shown is only illustrative and that the invention may be carried out by other means.

What I claim as new and desire to secure by Letters Patent of the United States is:

50 1. A time switch including a clock having a hollow hour hand shaft, a minute hand shaft extending through the hour hand shaft, a timing motor for driving said shafts at different desired rates, a clock dial having an outer stationary time graduated section and an inner circular section separated from each other by a circular slit, the inner section being secured to and driven by said hollow shaft and having a radial hour hand indication thereon, a switch operating member 55 splined on said hollow shaft so as to rotate therewith but movable axially thereon, means for urging axial movement of said member in one direction, a catch stop for normally preventing such movement but permitting movement in the opposite direction, said catch stop comprising a part rotated with said member and a part having a handle extending through said circular slit and manually adjustable about said shafts, said parts having one relatively rotary position where the stop catch is ineffective to prevent axial move-

ment of said member, and a switch operated by the axial movement of said member.

2. A time switch including a clock having a hollow hour hand shaft, a minute hand shaft extending through the hour hand shaft, a timing motor for driving said shafts at different desired rates, a clock dial having a circular central opening concentric with said shafts and having a time graduated scale flanking said opening, means driven by said shafts for indicating time on said scale, a switch operating member splined on said hollow shaft so as to rotate therewith but movable axially thereon, resilient means for urging said member axially of said shaft in one direction, a catch stop having a part rotated with said member and a part having a handle extending through the circular opening in said dial part and indicating on said time scale for manually adjusting said part about said clock shafts, said catch stop preventing the axial movement of said member in the direction urged by said resilient means except when the parts of said catch stop are in one relatively rotary position, manual means for axially moving said member against the urge of said resilient means, said movement being permitted in all relatively rotary positions of the catch stop parts and switching means operated by the axial movement of said member.

3. A time switch comprising a time driven shaft, time indicating means comprising a circular time dial, and means indicating thereon one of which is stationary and one of which is driven by said shaft, a switch, means for operating said switch comprising a member splined to said shaft to rotate therewith and to move axially thereon, spring means for moving said member along said shaft to operate said switch and means for determining the time of such operation comprising a stop normally preventing axial movement of said member and comprising a part on and rotated with said member and a normally stationary part concentric with and adjustable about said shaft, said stop parts allowing axial movement of said member in the direction urged by said spring only in one selected relatively rotary position of said parts, and an arm integrally connected with the normally stationary stop part and extending to and indicating on the circular time dial for manually adjusting the rotary position of such stop part.

4. A time switch including a clock having a hollow hour hand shaft, a minute hand shaft extending therethrough, a timing motor for driving said shafts at different desired rates, a clock dial having a central opening concentric with said shafts adjacent the forward ends thereof, means driven by said shafts for indicating time on said dial, a switch operating member splined on said hollow shaft so as to rotate therewith but movable axially thereon, a spring for urging said member forward along said hollow shaft, means for controlling first and second forward movements of said member comprising a pair of normally stationary stop plates at different axial positions along said hollow shaft having central openings concentric with said hollow shaft, and a spring catch secured to and rotated with said member having extended and retracted radial positions such as to prevent or permit its passage through the openings in said plates, each plate

having a radial slot in its inner periphery of such dimensions as to allow the catch to pass forward therethrough in one relatively rotary position of catch and plate, levers extending from each stop

5 plate through the central opening in the clock dial and indicating on said dial by means of which the stop plates may be manually and independently rotated to desired positions to determine the times of the first and second forward 10 movements of the switch operating member, and a switch operated by the first and second forward movements of said member.

5. A time switch including a clock having a hollow hour hand shaft, a minute hand shaft 15 extending therethrough, a timing motor for driving said shafts at different desired rates, a clock dial having a central opening concentric with said shafts and having a time graduated scale flanking said opening, means driven by said shafts 20 for indicating time on said scale, a switch operating member splined on said hollow shaft so as to rotate therewith but movable axially thereon, a compression spring coiled about said hollow shaft to the rear of said member for urging the member 25 forward along said shaft, a resilient catch part secured to said member, and rotatable therewith, a plurality of stops at different axial positions with which said catch part cooperates to control the progressive forward step by step axial movement 30 of said member, each stop preventing the forward movement of said catch beyond such stop except in one relatively rotary position of the catch and stop, arms extending from each stop member through the dial opening and indicating 35 on the time scale for individually and manually rotating the stops, switching means operated by the axial movement of said member and means for moving said member to the rear against the tension of said spring.

40 6. A time switch comprising a time driven shaft, a clock dial adjacent the forward end of said shaft, having an outer stationary part carrying a time scale and an inner part secured to and driven by said shaft and having a time indicating hand indicating on the stationary scale, a switch, means for operating said switch comprising a member splined on said shaft to rotate therewith and move axially thereon, a spring for moving said member forward and axially of said shaft, a stop catch for normally preventing such movement comprising a resilient catch on and rotated with said member and a pair of washer-shaped stop plates at different axial positions forward of said member and having inner peripheries concentric with and spaced from said shaft in approximate axial alignment with the path of rotation of said catch, said catch and stop plates serving to control the forward axial movement of said member, each plate having a radial slot in its inner periphery to allow the catch to pass therethrough in one relatively rotary position of the catch and plate, levers extending from said stop plates between the dial parts for rotatively adjusting said plates with 45 respect to the time scale, and a stationary clock plate having a circular opening for rotatively supporting the rear stop plate, the forward stop plate being rotatively supported between the rear clock plate and the rear of the inner clock dial part, both stop plates being rotatively supported 50 concentric to said shaft.

ROBERT HERMANN.
